UNITED STATES PATENT OFFICE.

THOMAS BELAIR, OF MONTREAL, QUEBEC, CANADA.

COMMERCIAL TRAVELER'S DISPLAY-TRUNK.

1,380,861.

Specification of Letters Patent. Patented June 7, 1921.

Application filed July 15, 1919. Serial No. 311,071.

To all whom it may concern:

Be it known that I, THOMAS BELAIR, a subject of the King of Great Britain, and resident of the city of Montreal, Province 5 of Quebec, Dominion of Canada, have invented certain new and useful Improvements in Commercial Travelers' Display-Trunks, and do hereby declare the following to be a full, clear, and exact description 10 of same.

This invention relates to the display of sample articles, appertaining particularly to trunk equipment utilized by commercial salesmen for the transportation and display 15 of their samples, the equipment being adapted for use in connection with any particular line of goods and especially advantageous for the transportation and displaying requirements of the lines of smaller sized merchandise in which the range is generally 20 large and varied in character.

Travelers' samples have, in most instances up to the present time, been packed in the ordinary manner for transportation, that is 25 to say the samples have been placed one upon the other in a more or less unrelated manner due to the exigencies of size, shape and available space. While the confusion naturally resulting from this has been partially avoided by the provision of specially 30 formed compartments or trays which standardize to a certain degree the order of packing and position of samples, present arrangements continue inadequate for the securing 35 of the desired rapid and comprehensive display without confusion, and the adaptability of the display for quick re-packing in readiness for transportation. This inadequacy of existing arrangements is due in considerable 40 extent to the time expending necessity for piecemeal removal from the trunk of either the samples themselves or the several compartments or trays containing them, their special arrangement for most advanta- 45 geous disposition determined by available surroundings each time a display is made at a different location and the subsequent piece- 50 meal repacking of the samples, the latter procedure possibly requiring more time than their removal owing to the probable necessity for particular arrangement in accom- 55 modating them within the available trunk space.

In recognition of the foregoing drawbacks 55 in present arrangements for travelers' samples, I have conceived the idea of equip-

ping a trunk or the like, with an expanding sample supporting stand specially constructed to be readily moved out of or into the trunk, preferably without detachment 60 therefrom. The object of this novel arrangement is to provide for a comprehensive display through the medium of the expanding stand and furthermore to permit of the entire line on view being handled as a whole 65 either for removal from or storage within the trunk, thus without sacrifice to the completeness of the display, eliminating the excessive expenditure of time and labor necessitated by arrangements at present in use, 70 and a further object of the invention is to provide means whereby the trunk is constructed in such a form as to present a convenient displaying of garments or the like, such construction making it possible to show 75 the full length of the garments or the like and at the same time supporting the trunk during the displaying thereof.

In the precise embodiment of my invention certain details of construction have been developed with the object of securing the most acceptable application of the primary feature of the device, which latter with said 80 constructional features will be hereinafter more fully described and particularly pointed out in the appended claims.

For full comprehension, however, of my invention reference should be had to the accompanying drawings forming a part of this 85 specification, in which similar characters indicate the same parts and wherein—

Figure 1 is a perspective view of my improved sample displaying device, illustrating the stand raised from the interior of the trunk and partially expanded or opened to 95 expose the samples;

Fig. 2 is a vertical section on line 2—2 Fig. 1;

Fig. 3 is a perspective view of the trunk open and illustrating the stand in raised position;

Fig. 4 is an enlarged detail perspective view of one corner of the trunk;

Fig. 5 is a side elevation of the stand with a hanger device as adapted for the use of garment hangers; and

Fig. 6 is a detail sectional view of the handle connection and shaft mechanism.

Referring now to the drawings, 2 indicates a trunk which, in so far as my invention is concerned, may be of any desired dimensions 110 to suit requirements. The cover indicated at

3, is of the usual comparatively shallow box-like construction, hinged at 4 to the back of the trunk and provided with suitable fastening means 5 cooperating with a lock 6 at 5 the front of the trunk to secure the cover in closed position.

The display stand consists preferably of an open rectangular frame comprising top and bottom pieces 7 and side pieces 8. This 10 frame, which I prefer to form of inwardly facing angle irons suitably fastened together at the corners and braced as at 8^a, is of such a depth as to be easily accommodated within the trunk in an upright position and of 15 a width to be slidably located between the trunk ends. A series of sample supporting members such as vertically disposed panels 9 to be hereinafter more fully described, are suitably supported between the top and bottom 20 pieces 7 and extend forwardly from the frame, the panels being adapted to have the samples attached thereto permanently in so far as successive showings of same are concerned. The extent of the panels is determined 25 by requirements and the trunk is constructed of such a width from front to rear as to properly accommodate them.

The frame of the stand is located in the rear of the trunk and the panels, with the 30 samples attached thereto, extend forwardly, both frame and panels supported thereby being adapted to be raised out of the trunk and lowered thereinto by means which will now be described.

35 A shaft 10 located within the cover near the front or free edge thereof, is rotatably mounted at its opposite ends in bearings 11 carried by the cover, one end of the shaft passing through one bearing and adapted 40 to have a removable crank handle 12 fitted thereto whereby the shaft can be rotated. A preferred means of connecting the shaft and handle consists in forming a key-hole socket 13 in the end of the shaft for the reception 45 of a correspondingly formed reduced end 14 of the handle. Flexible lengths 15 consisting of cable wire or the like are attached at one of their ends to the shaft and at their opposite ends to the side 50 frame pieces 8, this latter connection being preferably formed through the medium of eye-bolts 16 having screw-threaded connections with brackets 17 carried by the angle irons within the angles thereof, the bolts 55 being bent to clear the inner edges of the side pieces. By winding the wires 15 upon shaft 10 the display stand is raised and upheld during the raising operation and when raised it will fall at an angle inclining 60 to the rear of the trunk and, through such inclination, the panels will be free to swing clear of the top of the trunk and at the same time remain open when moved to the required position for display. The 65 shaft 10 as it is rotated to elevate the stand

is held against turning in the opposite direction by means of a ratchet 18, carried by the shaft, and a spring pawl 19 carried by the cover and engaging the ratchet, the stand being thus maintained in its elevated position. 70

Suitable means such as a chain 20 with a ring 21 is attached to the pawl to enable same to be disengaged from the ratchet and permit the stand being lowered into the 75 trunk.

In order to brace the hinged cover against the weight of the stand, braces 22 are provided, these braces being rigid from end to end, pivoted at their upper ends to the interior of the cover and provided with eyes 23 at their lower ends. These eyes are adapted to be slipped over pins 24 extending inwardly from the ends of the trunk near the top, the rigid braces crossing over the 80 cover hinge and upholding the cover. Adjustment in the length of the braces is provided for by making the eyes 23 in the form of eyebolts screwed to the lower ends of the braces which latter are bent inwardly 85 for this purpose.

The rear interior corners of the trunk are provided with vertical rails 25 to guide the upward and downward movements of the 90 frame and through it, the stand as a whole, the forward margins of the rails presenting projections or overhanging portions 26 which embrace the forwardly extending flanges of the frame and so form recesses 95 therefor. The bottom frame piece is cut 100 away at 27 to clear the projections 26. If desired ball bearings 27^a or other suitable anti-friction devices can be mounted either on the rails or on the side pieces as shown to facilitate the movements of the stand. 105

The rails 25, combined with a centrally located vertical rubbing plate 28 carried by the rear of the trunk, guide the stand throughout from side to side and enable same to be moved up and down in a steady 110 manner and as it is proposed to maintain the same within the rails when the frame is in its uppermost position, these rails at all times brace and steady the stand. Vertical guide rods 29 anchored in the bottom of the 115 trunk extend loosely through holes in the bottom pieces 7 of the frame and have enlarged upper ends 30 to so limit the upward movement of the stand as to hold the frame within its rails as just mentioned and maintain the stand as a component part of the 120 trunk.

My invention contemplates constructing the display stand in such a manner that while the panels may be arranged in substantially close proximity to each other and so occupy a relatively small space, they can when it is desired be moved or spread apart and when so opened out occupy a considerably greater space and expose a more ex- 130

tensive display surface to provide for a complete view of the articles carried by the panels. This expansion of the stand may be accomplished in different ways; for example, when utilizing panels as in my preferred construction, embodied herein, the panels would be pivoted at one of their ends to the frame so that their major extent is capable of swinging through a considerable arc from a close relation one with the other to a widely separated position. The stand is thus capable of adjustment from an expanded position wherein it exposes extensive displaying surface to a contracted position occupying a considerably reduced space and providing for convenient and compact packing during transportation.

While the panels 9 may be of any desider construction, it is considered that the most advantageous results may be secured by forming them of wallboard, fine wire mesh, burlap or the like and binding them with metal strips as at 31. With this construction the inner or rear binding strips can be utilized to form the pivotal connection between the panels and the frame by forming said strips to present eyes or sleeves 32 loosely embracing vertical pivot or hinge rods 33 carried by and extending between the top and bottom frame pieces 7. Each panel may be separately pivoted in the manner above described but as illustrated in the accompanying drawings the panels are pivoted in pairs, the eyes or sleeves 32 of each panel of a pair being spaced along the height of the panel, those of each staggered with relation to the other and the eyes of both panels of the pair embracing the same rod as shown clearly in Fig. 1. The idea of having the panels pivoted in pairs upon the stand is that each pair may be opened or taken apart to more easily mount the articles on the outside and fasten them from the inside of each panel and when filled the panels are brought together and clamped by means of bolts or the like, but I prefer to clamp or secure them together by the same bolt that I use in securing the distance pieces hereinafter described in the panels.

The panel pivot rods 33 are each removably carried in holes 34 in and spaced longitudinally of the frame pieces 7, being upheld by a head 34^a at the top and firmly fastened by a nut 34^b at the bottom, thus enabling the panels to be readily removed when desired. Furthermore the number of holes 34 in each of the frame pieces exceed the number of pivot rods employed and therefore permit the spacing of the rods being varied by their insertion into different holes, the holes and rods thus coöoperating in establishing an adjustment in the spacing of the pivots of the panels and the bodily spacing of the latter as distinguished

from the spacing of same when swung upon their pivots.

The display stand can if desired, be modified as illustrated by Fig. 5 for the accommodation of garments and in this construction the panels are eliminated, the upper ends of the rods 33 extended forwardly at 33^a and formed with eyes or hooks 33^b upon which a garment hanger, indicated at 38^c, may be suspended. 75

The height and position of the panels are such that when the stand is raised to its upper or displaying position, their lower edges will be spaced above the upper edges of the trunk and be free to swing over the latter. In this way the stand can be expanded to a considerable extent beyond the sides of the trunk by swinging the panels outwardly to opposite sides and exposing to view the full range of articles. A partial extension of the stand is illustrated by Fig. 1. 80 85

When the stand is to be lowered into the trunk the panels are swung into close proximity to each other, the pawl disengaged from the ratchet and the lowering of the stand gradually effected through the control provided by the handle 12. Just previous to the entry of the lower edges of the panels into the trunk, arms 36 pivoted to opposite interior sides of the trunk ends near the front and top thereof, are swung from an upwardly and outwardly extending position to an inwardly extending position bearing against the end panel to confine and 90 guide the free ends of all the panels into the trunk, anti-friction rollers 37 being mounted in vertical position on the ends of the arms 36. This preliminary concentration of the panels is supplemented when the stand approaches the bottom of the trunk, by means of downwardly and inwardly inclined grinding surfaces at opposite sides of the trunk and near the bottom and front thereof. These surfaces are presented by 95 transversely disposed triangular blocks 38 which finally automatically close the panels and, with the arms 36 and arms 40 to be now described, firmly maintain and brace them 100 in their closed position and prevent the 105 stand shifting to either side. 110 115

Distance pieces are preferably provided between adjacent panels in order to avoid such close approach of one to the other as 120 to permit contact of articles upon opposing surfaces of the closing or closed panels. These distance pieces consist, for example, of arms similar to the beforementioned arms 40 which are rigid and extend outwardly from the panels in position to engage adjacent ones, the arms being attached to the panels by bolt-and-nut fastenings 40^a in order that they may be readily removable to permit arms of varying lengths be- 125 130

ing used according to the spacing required between the panels for differently sized articles. Horizontally disposed, rubber mounted rollers 41 are carried by the outer ends 5 of the arms to accommodate any slight relative movement of the panels and the bolt-and-nut fastenings 40^a are also utilized for holding each pair of panels together as before suggested.

10 While the capacity of the stand can be varied to suit different requirements, the combined superficial area of such number and size of panels as it may be desired to employ also the adaptability of the panels 15 for intimate and compact packing within a small space, provide for considerably larger and more conveniently utilized displaying facilities within a given compass than are offered by the present cumbersome arrangements.

When the stand is housed as above described, the handle 12 is removed and the cover closed by slipping the lower ends of the braces 22, inwardly from the pins 24 25 and lowering the cover over the panels and frame. The secure bracing of the stand which is obtained by the arms 36, 40 and blocks 38 is added to by so constructing the cover with a filler strip 45 along its rear 30 inner side that when it is closed it will bear down upon the top of the stand at the rear and prevent the possibility of upward shifting thereof. The shaft 10 bears upon the stand at front and constitutes the front 35 bracing. The lower ends of the braces 22 slip down behind straps 48 carried by and extending between front and rear of the ends of the trunk about midway between top and bottom thereof, these straps confining the braces and securing same in position 40 when the trunk is closed.

It will be apparent from the foregoing that with the samples attached to the panels, the complete assortment of articles 45 comprising the display is capable of being handled as a whole, both when it is desired to remove them from the trunk for display purposes and when they are to be packed for transportation. Through the 50 medium of this arrangement the whole display can be very quickly removed from the trunk and by swinging open the panels spread into view and as speedily gathered together by closing the panels, and packed 55 into the trunk thus eliminating the necessity for a separate removal and subsequent packing of each article or tray of articles. Furthermore the expenditure of time and exercise of care to present the 60 different articles in their most advantageous arrangement relatively to one another heretofore necessitated by the piece-meal handling of the articles each time they were displayed at a different location, is avoided as the articles can be ini-

tially fixed to the panels in the most suitable arrangement and handled in such arrangement as a whole for transportation between successive displays.

The construction of trunk I prefer to use 70 as being most suitable or adaptable for my device consists in having the ends and front free of the bottom of the trunk, the front being divided vertically midway into two portions 50 and 51, each half portion being 75 formed integral with either one of the ends 52 and 53 while the rear of the trunk adjacent to the corners 54 is provided with ordinary hinges 55 adapted to have such ends secured thereon. When the articles are 80 being displayed the hinged ends with their respective front half portions 50 and 53 will be swung open to the rear of the trunk and the bottom 56 of each end will bear upon the floor or the like and act as a support for 85 the stand. During transportation the ends and front half of the trunk are swung into place and secured to their respective parts and connected by any suitable fastening devices 57 and 58. 90

What I claim is as follows:

1. In combination, a trunk having a hinged cover, a display stand including a frame normally located within the trunk and capable of supporting sample articles, 95 a shaft rotatably mounted at its ends in the sides of the cover near the free end of the latter, a flexible length attached to each side of the frame and to the shaft and adapted, after the cover has been raised, to 100 be wound upon the shaft to elevate the stand, independently of any movement of the cover, means for rotating the shaft in one direction and means to temporarily prevent its turning in the opposite direction. 105

2. In combination, a trunk, a display stand including a rigid frame, such stand being normally located within the trunk and capable of supporting sample articles and adapted to be raised from the confines 110 of the trunk, the frame being rigidly formed of top, bottom and side bar portions and occupying a limited vertical space at the rear of the trunk only, the bottom bar portion having perforations to accommodate guide rods and vertical guide rods passing through said perforations, anchored in the bottom of the trunk and serving to limit the upward movement of the stand. 115

3. In combination, a trunk, a stand including a series of relatively movable panels adapted to be moved from a position close to one another, to a more widely separated position, said stand being located within the trunk, mechanism for raising and lowering 120 the stand out of and into the interior of the trunk and means for automatically guiding the panels into their close position one with the other as they are being lowered into the trunk and for maintaining such position 130

when the panels are housed within the trunk.

4. In combination, a trunk, a stand located within the trunk and including a series of relatively movable sample supporting members, mechanism for moving the stand into and out of the interior of the trunk and means for automatically moving the sample supporting members toward each other when the stand is moved into the trunk.

5. In combination, a trunk, a sample supporting stand located within the trunk and including a series of pivoted panels, means for raising and lowering the stand out of and into the interior of the trunk, guiding devices located near the top of the trunk and adapted to engage and preliminarily close the panels one upon the other during the initial lowering movement of the stand into the trunk and guiding devices located near the bottom of the trunk and adapted to finally close the panels one upon the other during the final lowering movement of the stand into the trunk.

6. In combination, a trunk, a sample supporting stand located within the trunk and including a series of pivoted panels, means for raising and lowering the stand out of and into the interior of the trunk, movable guiding devices located near the top of the trunk and adapted to engage and preliminarily close the panels one upon the other during the initial lowering movement of the stand into the trunk and stationary guiding devices located near the bottom of the trunk and adapted to finally close the panels one upon the other during the final lowering movement of the stand into the trunk.

7. In combination, a trunk, a sample supporting stand located within the trunk and including a series of pivoted panels, means including a shaft arranged within the cover, for raising and lowering the stand out of and into the interior of the trunk, steadyng devices projecting inwardly from the ends of the trunk adapted to engage and bear upon opposite sides of the lowered panels near the top and bottom edges thereof, an additional steadyng device located within the cover at the rear thereof adapted to engage and bear upon the rear top edges of the lowered panels, and the said shaft being also adapted to engage and bear upon the front top edges of the lowered panels.

8. In combination, a trunk, a display stand located within the trunk, such stand including a frame and a series of panels pivoted to the frame, the latter being rigidly formed of top, bottom, and side bar portions and occupying a limited vertical space at the rear of the trunk only; means for raising and lowering the frame, and vertical guide rails fitted within the rear

corners of the trunk for the guidance of the frame in the upward and downward movement thereof, a portion of such rails overhanging the sides of the frame and the lower side or flange of the frame being notched to accommodate such overhanging portions of the rails.

9. A display stand consisting of a frame, a series of rods supported at their ends in the top and bottom of the frame and panels mounted upon the rods to swing with relation to each other, each panel presenting eyes formed along its rear edge and adapted with another panel to form a pair the eyes of which embrace one rod common to the two panels; spacing devices carried by and projecting from one side of each pair of panels with means serving both to attach the spacing devices to the pair of panels and also hold together the two panels constituting the pair.

10. A display stand consisting of a frame, a series of rods supported at their ends in the top and bottom of the frame and panels mounted upon the rods to swing with relation to each other, each panel presenting eyes formed along its rear edge and adapted with another panel to form a pair the eyes of which embrace one rod common to the two panels; spacing devices consisting of an arm and roller carried by and projecting from one side of each pair of panels with bolt and nut serving both to attach the spacing devices to the pair of panels and also hold together the two panels constituting the pair.

11. In combination, a trunk having a hinged cover, a display stand including a frame normally located within the trunk and capable of supporting sample articles, a shaft rotatably mounted at its ends in the sides of the cover near the free end of the latter, a flexible length attached to each side of the frame and to the shaft and adapted, after the cover has been raised, to be wound upon the shaft to elevate the stand, independently of any movement of the cover, means for rotating the shaft in one direction, means to temporarily prevent its turning in the opposite direction, and a device for bracing the cover in its raised position to sustain the weight of the stand.

12. In combination, a trunk, a cover hinged to the trunk, a display stand located within the trunk, pins extending inwardly from the ends of the trunk, mechanism mounted in the trunk cover and adapted, after the cover has been raised, to elevate and lower the display stand out of and into the trunk, a device for maintaining the stand in its raised position and a device for bracing the cover when raised to sustain the weight of the stand, such bracing device including braces which are rigid throughout their length and pivoted at their upper ends to

the cover; the lower ends of the braces presenting eyes adapted when the cover is in its raised position, to be slipped over and upheld by said pins.

- 5 13. In combination, a trunk, a cover hinged to the trunk, a display stand including a frame located within the trunk and mechanism mounted in the trunk cover and adapted, when the cover is raised, to elevate and lower the display stand out of and into the trunk, such mechanism including a shaft rotatably mounted at its ends in the sides of the cover near the free end of the latter, a flexible length attached to 10 each side of the frame and to the shaft and adapted to be wound upon the latter, a handle detachably secured to one end of the shaft, a ratchet wheel rigidly mounted upon the shaft, a spring pawl carried by the cover and engaging the teeth of the ratchet and a flexible length attached to the pawl whereby the latter can be disengaged from the ratchet wheel.

14. In combination, a trunk, a cover hinged to the trunk, vertical rails disposed adjacent the rear corners of the trunk, a display stand including a frame arranged vertically between said rails, panels pivoted to the frame and extending therefrom forwardly toward the front of the trunk, arms pivoted to the opposite interior ends of the trunk near the top and adapted to be moved to engage the end panels, blocks located at opposite sides of the bottom of the trunk near the front thereof and presenting downwardly and inwardly inclined surfaces adapted to engage the end panels, a shaft rotatably mounted at its ends in the cover of the trunk near the free edge thereof, flexible lengths attached to said shaft and frame of the stand and adapted to be wound upon the former to raise the stand, a handle removably attached to one end of the shaft, a ratchet wheel rigidly mounted upon the shaft, a pawl engaging the ratchet teeth and braces for the cover.

15. In combination, a trunk, a cover hinged to the trunk, vertical rails disposed adjacent the rear corners of the trunk, a vertically arranged plate carried by the rear of the trunk between said rails, pins extending inwardly from the ends of the trunk, a display stand presenting holes in the bottom thereof and including a frame arranged vertically between said rails and guided thereby and by said plate, panels pivoted to the frame and extending therefrom forwardly toward the front of the trunk, rigid arms carried by and extending outwardly from the panels near their free ends and adapted to limit the approach of the panels toward each other, arms pivoted to the opposite interior ends of the trunk near the top and adapted to be moved to engage the

end panels, blocks located at opposite sides 65 of the bottom of the trunk near the front thereof and presenting downwardly and inwardly inclined surfaces adapted to engage the end panels, a shaft rotatably mounted at its ends in the cover of the trunk near the free edge thereof, flexible lengths attached to said shaft and frame of the stand and adapted to be wound upon the former to raise the stand, vertically arranged rods anchored to the bottom of the trunk, located in 70 the holes in the bottom of the frame and presenting enlarged upper ends limiting the upward movement of the stand, a handle removably attached to one end of the shaft, a ratchet wheel rigidly mounted upon the 75 shaft, a pawl engaging the ratchet teeth, braces pivotally attached at their upper ends to the cover and presenting eyes at their lower ends adapted to be slipped over said pins, straps attached to the interior surfaces 80 of the trunk and extending from front to rear thereof in position to receive said braces when the cover is closed and a strip filling in the hinged corner of the cover and adapted to bear upon the top of the display stand 85 when the cover is closed.

16. In combination, a trunk, a cover hinged to the trunk, movable ends hinged to the back of the trunk, the front being adapted to have each half movable with the ends 95 thereof, a display stand located within the trunk, pins extending inwardly from the ends of the trunk, mechanism mounted in the trunk cover and adapted when the cover is raised, to elevate and lower the display 100 stand out of and into the trunk, a device for maintaining the stand in its raised position and a device for bracing the cover in its raised position to sustain the weight of the stand.

17. In combination, a trunk, a cover hinged to the trunk, movable ends hinged to the back of the trunk, a divided front adapted to have each half rigid with the ends and movable therewith, such ends and 110 front halves being free of the bottom of the trunk, and each end and half being adapted to swing to a position in rear of the trunk and in line with the open ends thereof, means for locking the lower ends of said 115 ends and front halves to the bottom of the trunk and adjacent edges of the front halves together, a display stand located within the trunk, pins extending inwardly from the ends of the trunk, mechanism mounted in the trunk cover and adapted, when the cover is raised to elevate and lower the display stand out of and into the trunk, a device for maintaining the stand in its raised position and a device for bracing the cover in its 120 raised position to sustain the weight of the stand.

THOMAS BELAIR.
